[57] CLAIM

The ornamental design for a printer cabinet, substantially as shown and described.

DESCRIPTION

FIG. 1 is a front, top and right side perspective view of a printer cabinet showing our new design;

FIG. 2 is a left side elevational view thereof;

FIG. 3 is a right side elevational view thereof;

FIG. 4 is a rear elevational view thereof.

The diagonal shading shown on the cover in FIGS. 1 through 4 depicts a translucent material.

FIG. 1

FIG. 2

FIG. 3

FIG. 4
